STORE

Robert J. Harper, Scarsdale, N.Y., assignor to Northwestern Refining Co., St. Paul Park, Minn., a corporation of Minnesota

Filed July 30, 1963, Ser. No. 76,043

Term of patent 14 years

FIGURE 2 is a rear perspective view showing the rear and the other end of the said store.

I claim:

The ornamental design for a store, as shown and described.
